UNITED STATES PATENT OFFICE.

GEORGE W. HARRIS, OF STURGIS, MICHIGAN.

WATCH-MAKER'S TOOL.

SPECIFICATION forming part of Letters Patent No. 268,664, dated December 5, 1882.

Application filed September 25, 1882. (Model.)

To all whom it may concern:

Be it known that I, GEORGE W. HARRIS, a citizen of the United States of America, residing at Sturgis, in the county of St. Joseph 5 and State of Michigan, have invented certain new and useful Improvements in Watch-Makers' Tools; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in watch-makers' tools, and it is designed more especially for setting ruby and jewel pins in the roller-table of a time-keeper, or for similar purposes.

My invention consists in the construction of a jewel-holder or pinchers, and in providing said holder with a base having extension at right angles with the jaws of the pinchers; also, in providing the pinchers with a movable 25 base having openings or slots of different sizes, as will be hereinafter more fully set forth, and pointed out in the claims.

In the annexed drawings, Figure 1 is a perspective view of my invention, showing the 30 same and its relative position when applied to the roller-table of a watch to set the ruby or jewel pin. Figs. 2 and 3 are side views, showing the implement opened and closed upon the ruby-pin. Fig. 4 is a front view, showing the 35 foot turned horizontally. Figs. 5, 6, and 7 are perspective views of the roller-tables, showing the relative position of the ruby or jewel pin therewith. Fig. 8 is a sectional view taken through the line $x-x$ of Fig. 4, and Fig. 9 is a 40 detail view, showing the relative position of the parts when inserting a jewel in the roller-table from which the balance-staff has been removed.

In the annexed drawings, A represents the 45 handle of my improved implement, which handle consists of a single strip or band of spring metal, which is bent or shaped at its upper part so as to form a loop, having the upper part curved. The base of the loop is formed 50 by the sides converging toward each other at the point a , at which they press upon each

other. One of the members, b , of this handle is curved outwardly from the portion a to its end b' , which projects below the other member, c , which is straight from the abutting point a to its end. Attached to the member c , so as to be capable of being reversed thereon, is a plate, B, the ends of which are bent at right angles with the body of the same. The back or body of the plate B has at its vertical 60 ends small openings $e e$, which are preferably V-shaped, the wider portion of these openings being adjacent to the end of the member b' of the pinchers, so as to provide a depression which will hold the roller-jewel more securely 65 and in a vertical position. The ends of the plate B, which are formed at right angles to the same, are provided with central longitudinal slots $d d$, which are of different sizes, and extend from the openings or depressions $e e$ to 70 the end of the horizontal portions of the plate B. The object of forming this plate with angular feet or rests, which are secured to the member c of the handle A, so as to be rotated thereon, and providing the same with depressions $e e$ and slots $d d$ of different sizes, is to 75 provide a means whereby the ruby-pin or jewel i will be held between the pinchers in a vertical position, and to provide an implement which can be used in setting the jewel in roller-tables having balance-staffs of different diameters.

My invention may be used for the purpose herein set forth as follows: The ruby-pin or jewel is grasped between the jaws of the implement, so that it will rest within the V-shaped opening in the foot B, wherein it is held by the end b' of the member b , a portion 85 of the jewel extending below the jaws; which portion of the jewel is inserted and secured in 90 the roller-table. If the balance-staff is in the roller-table, the slotted foot d of the plate or foot B will be placed over the balance-staff and will rest upon the roller-table.

By the use of the tool hereinbefore described the jewel-pin is held and inserted in the roller-plate properly and easily.

Having thus described my invention, what I claim as new, and desire to secure by Letters Patent of the United States of America, is— 100

1. In a watch-maker's tool, the handle formed of a single band of metal sprung together near

its end and at a portion intermediately between the ends, substantially as shown.

2. The handle A, having members of different lengths and provided with a slotted foot or rest attached to the shorter member, substantially as described.

3. The handle A, consisting of a single band of metal sprung together so as to abut at a portion above the base, and provided with a curved member on one side and a straight member on the other, which is provided with a reversible plate having slotted feet extending outwardly at right angles therewith, for the purpose set forth.

15 4. In a watch-maker's tool, the tweezers having members of different lengths sprung together, the shorter member being provided with a plate having ends bent at right angles,

with slots of different sizes, said plate being pivoted to the shorter member of the handle, substantially as shown.

5. As a new article of manufacture, a tool for watch-makers' use, consisting of a handle made of one piece of metal sprung together at a point above the base, and provided with a plate having recesses e e and slotted end portions bent at right angles with the body of the plate, said plate being pivoted to one end of the handle, substantially as shown and described.

In testimony whereof I affix my signature in presence of two witnesses.

GEORGE W. HARRIS.
